United States Patent Office.

WILLIAM STENGER AND ALOIS BEYRNHEIMER, OF JEFFERSON, OHIO.

Letters Patent No. 66,410, dated July 2, 1867.

IMPROVED BED-BOTTOM.

The Schedule referred to in these Letters Patent and making part of the same.

TO ALL WHOM IT MAY CONCERN:

Be it known that we, WILLIAM STENGER and ALOIS BEYRNHEIMER, of Jefferson, in the county of Harrison, and in the State of Ohio, have invented certain improvements in "Bed-Bottoms;" and do hereby declare that the following is a full, clear, and exact description thereof, reference being had to the accompanying drawings and to the letters of reference marked thereon, making a part of this specification.

In the annexed drawings, A represents a bedstead of the ordinary manufacture. The cord composing the bottom of this bedstead, instead of being in one piece, is a series of short pieces which cross each other, and are attached at each end and side of the bedstead.

Our invention consists in the devices for attaching these cords to the bedstead, and in so attaching them to give elasticity to the bed-bottom.

At suitable distances apart there are small narrow slots cut into the sides and ends of the frame of the bed for the insertion of the ends of narrow rubber bands, which connect the bent rods a a a. It will be seen that these rods are so constructed as to allow the rubber bands to loop around their rear ends, while the front ends are so compressed as to catch and hold the knots tied in the ends of the bed-cord and hold it fast.

In constructing a bed-bottom, we first cut the narrow slots in the rails and lap the narrow rubber strips around the rear end of the loops a, and then insert the ends of the rubber in slots and wedge (x) them by means of a narrow strip of wood so that the loops and bands are thus firmly attached to the bedstead. The cords are then tied with knots at each end, and extended from end to end of the bedstead and caught in the loops. When the long cords y are thus secured, the short cords z are also tied and crossed from side to side of the bedstead, but overlapping and thereby connecting the same to the long cords y. A bed-bottom thus formed can be readily put together, and will be found both elastic and durable.

Having thus fully described our invention, what we claim as new, and desire to secure by Letters Patent, is—

The loops a a, bands z z, and wedges x x, when used upon the bedstead-frame in combination with the cords z and y, in the manner substantially as and for the purposes set forth.

In testimony that we claim the foregoing, we have hereunto set our hands this 16th day of March, 1867.

WM. STENGER,
ALOIS BEYRNHEIMER.
